UNITED STATES PATENT OFFICE.

LÉON AUGUSTE MAZELLIER, OF ST.-PIERRE LE MOUTIER, FRANCE.

ELECTRIC IGNITION-PLUG.

1,084,808.

Specification of Letters Patent.

Patented Jan. 20, 1914.

Application filed February 9, 1911. Serial No. 607,611.

To all whom it may concern:

Be it known that I, LÉON AUGUSTE MAZELLIER, a citizen of the Republic of France, residing at 16 Rue de Paris, St.-Pierre le Moutier, Nièvre Department, in the Republic of France, engineer, have invented certain new and useful Improvements in Electric Ignition-Plugs, of which the following is a specification.

10 This invention relates to electric ignition plugs and has for its object to so construct a plug of this character as to avoid the rupture of the insulation under the influence of the expansions, and to facilitate the construction, the mounting, and the keeping in good order of its several parts.

By way of example the accompanying drawings show the essential arrangements of such plug.

20 Figure 1 is a sectional view on the axial line of the plug; and Fig. 2 is a bottom plan view.

1 designates a metal piece, called a socket, which is intended to be screwed into the wall 25 of the explosion chamber of the engine. Such socket comprises, at the outside, a polygonal head and a threaded part; at the inside, a cylindrical cavity having a shoulder 2 at its upper part; the top of the head 30 has a circular shoulder 3. The electrode consists of a rod 4 the upper part of which is threaded and of which the lower part carries an enlarged part or shoulder 5 and a cut disk 6 which is riveted on its end.

35 7 designates a piece of porcelain of tubular shape, having a shoulder 8 at the outside and a shoulder 9 at the inside, so that its wall is Z shaped, in longitudinal section. Such piece is inserted from below and upward into the cavity of the socket so that the shoulders 2 and 8 impinge against each other; the electrode is another part inserted from below and upward through the piece 7 so that the shoulder 5 impinges against 45 the shoulder 9; the periphery of the disk 6 thus lies at a short distance from the wall of the socket.

On the shoulder 3 is loosely embedded a cylindrical socket 10, on which is mounted 50 a porcelain cap 11. The latter is loosely engaged in the socket and rests on the latter by means of a shoulder 12 at the outside; it is provided with a central aperture or opening through which the electrode 4 passes 55 loosely. These several parts are held in

place by means of a nut 13 screwed onto the electrode in such a manner as to clamp all such parts together. In order to limit such clamping and render it constant, a spiral spring 18 is interposed between the nut and 60 the cap; such nut and the spring are housed in a cavity 19 of the cap, the bottom of which lies preferably at a short distance from the shoulder 12.

It is obvious that the piece of porcelain 7, 65 only held at its middle and having both its ends entirely free, can expand and contract without meeting with any resistance. Such condition is obtained without having to provide in the porcelain sudden variations of 70 thickness which give rise to rupture. Furthermore, as the planes of the shoulders 8 and 9 can be placed very near each other, the expansion of the porcelain between such planes is *nil* and has no influence on the 75 relative position of the metal pieces 1 and 5. Likewise, in placing the bottom of the cavity 19 near the plane of the shoulder 12, any influence of the expansion of the porcelain cap on the relative position of the 80 metal pieces 4 and 10, is avoided. The result is that should the pieces 4 and 10 be subjected to about the same temperature and be made of metals having about the same 85 coefficients of expansion, the variations of 90 temperature would not have any material influence on the pressure to which the porcelain pieces are subjected even if the spring 18 were done away with, the nut 13 then resting directly on the cap. The interposition of the spring 18 further increases the 95 constancy of the pressure and the security.

In order to allow of the inspection of the interior of the socket 10, apertures or openings 14 are provided in the latter. Such 95 apertures or openings may be closed by means of a cylindrical screen 15 turning with a slight amount of friction on the socket 10 and provided with a long gap 16. By bringing such gap in front of both the 100 apertures 14 as shown in the drawings, the interior of the socket 10 can be inspected, the space within such interior being almost dark, so that it will be seen at once whether the porcelain 7 is heated to a red heat or is 105 giving out sparks between the electrode 4 and the top of the socket 1. Furthermore, the outer air is enabled to circulate in the socket and cool the several parts. The drawings show in dotted lines a pipe 20 formed 110

on the screen 15 and allowing of air being blown into the socket 10 by means of a flexible pipe connected with a compressed air reservoir or fan, or the like. By turning the screen 15, the socket 10 can be completely closed, so as to be protected against the water, for instance when the motor-car is being washed.

The disk 6 is preferably cut as shown in Fig. 2; it is provided with two semi-circular openings 6^a and the arcs remaining on the periphery are divided by intervals 6^b; the disk thus forms a hub 6^c carrying two arms 6^d each of which terminates in quadrant arcs 6^e. That allows of obtaining sparks all around the disk, as with the electrodes having disks already known; and there is also obtained the advantage of allowing the gases to pass through the disk, which lessens the risk of greasiness, and the further advantage of being able to easily regulate the interval between the edges of the disk and the socket 1; in short, the disk is open worked and is extensible. Nevertheless, the invention is not limited to this kind of electrode.

It must be understood that such embodiment of the invention is only given by way of example and that the forms and proportions of the several parts hereinbefore described may be varied while remaining within the scope of the invention. For instance, the socket 10 may be made integral with the socket 1; the electrode may, on the other hand, be made of two or more pieces screwed or otherwise assembled together. Instead of porcelain, any other suitable material may be used for the insulation pieces 7 and 11. The spring 18 and the screen 15 may either be used or not, and obviously both the form and the arrangement of the apertures or openings in the socket 10 and in the screen 15 may be modified.

Claims:

1. An ignition plug comprising a metal 45 socket, a cylindrical socket resting on said metal socket and having lateral openings, a jacket rotatably mounted on said socket and having a peep hole which can be brought in register with one of the socket openings, 50 tubular pieces of porcelain supporting respectively the top of the cylindrical socket and the bottom of the metal socket, an electrode passing through said tubular pieces, and means on the electrode for clamping 55 said pieces on said sockets.

2. An ignition plug comprising a metal socket, a cylindrical socket resting on said metal socket and having lateral openings, a jacket rotatably mounted on said cylindrical socket and having a supply opening for the air and an opening for the escape of the air and adapted to serve as a peep hole to the interior of the plug, tubular pieces of porcelain bearing against the top of the 65 cylindrical socket and the bottom of the metal socket respectively, an electrode passing through said pieces, and means on the electrode for clamping said pieces on the sockets.

3. In an ignition plug, an electrode comprising a rod, a disk secured to one end of said rod, said disk being cut out to form a hub, two diametrically opposed arms and curved extensions extending from the end 75 of each arm in directions concentric to the hub, thus forming together a nearly complete ring.

In testimony, that I claim the foregoing as my invention I have signed my name in 80 presence of two subscribing witnesses.

LÉON AUGUSTE MAZELLIER.
